PORTABLE MERRY-GO-ROUND

Emery Salgo and Fred M. Drake, Reno, Nev.

Application May 29, 1950, Serial No. 10,263

Term of patent 14 years

(Cl. D34—5)

To all whom it may concern:

Be it known that we, Emery Salgo and Fred M. Drake, both citizens of the United States, residing at Reno, State of Nevada, have invented a new, original, and ornamental Design for Portable Merry-Go-Round, of which the following is a specification, reference being had to the accompanying drawing, forming a part hereof.

Fig. 1 is a front elevational view of a portable merry-go-round, showing our new design;

Fig. 2 is a top plan view thereof;

Fig. 3 is a fragmentary perspective view thereof, showing the lower base member in closed position; and

Fig. 4 is a perspective view thereof.

We claim:

The ornamental design for a portable merry-go-round, as shown.

EMERY SALGO.
FRED M. DRAKE.
